(57) **CLAIM**

The ornamental design for a breast perspiration pad, as shown in the drawings.

DESCRIPTION

FIG. 1 is a perspective view of a breast perspiration pad showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof, the right side elevational view being the mirror image thereof;

FIG. 7 is a perspective view of a second embodiment of the breast perspiration pad; and,

FIG. 8 is a top plan view thereof.

The broken lines in FIG. 7 represent the portion of the design, which forms no part of the claim.

1 Claim, 4 Drawing Sheets
